UNITED STATES PATENT OFFICE

116,987

DESIGN FOR A LAMP BASE

August O. Elting, Chicago, Ill.

Application July 20, 1939, Serial No. 86,125

Term of patent 14 years

To all whom it may concern:

Be it known that I, August O. Elting, a citizen of the United States, residing at Chicago, in the county of Cook and State of Illinois, have invented a new, original, and ornamental Design for a Lamp Base, of which the following is a specification, reference being had to the accompanying drawing, forming a part thereof, in which:

Fig. 1 is a side elevational view of the lamp base showing my new design; and

Fig. 2 is a top plan view with the reflector and base support illustrated by broken lines in Fig. 1 omitted.

The dominant feature of my design resides in the portion shown in solid lines.

I claim:

The ornamental design for a lamp base, as shown and described.

AUGUST O. ELTING.
